DECORATING APPARATUS

Clarence A. Heyne, Alton, Ill., assignor to Owens-Illinois Glass Company, a corporation of Ohio

Application March 31, 1941, Serial No. 386,075

10 Claims. (Cl. 101—124)

My invention relates to printing and decorating apparatus of the screen type in which the printing or decorating material is applied to the articles through a screen or the like. The invention in its preferred form is adapted for applying color designs or decorations to the surfaces of bottles or other round articles.

An object of the invention is to provide improved means for simultaneously applying decorations to different portions of the articles presenting round surfaces of different diameters as for example, the body and shoulder portions of a bottle.

A further object of the invention is to provide improved pneumatic operating and controlling mechanism for actuating the moving parts and automatically synchronizing and controlling the various operations.

Other objects of the invention will appear hereinafter.

Referring to the accompanying drawings:

Fig. 1 is a plan view of a decorating machine embodying the principles of my invention.

Fig. 2 is a front elevation of the machine.

Fig. 3 is an end elevation of the machine on a larger scale, parts being broken away.

Fig. 4 is a plan view of a portion of the machine including the screen carriages and the piston motor for operating them.

Fig. 5 is a longitudinal sectional elevation of the machine at the planes indicated by the line 5—5 on Fig. 3.

Fig. 6 is a sectional elevation at the plane of the line 6—6 on Fig. 2.

Fig. 7 is a detail view showing a chuck and its motor in section.

Fig. 8 is a fragmentary rear elevation of the machine, parts being shown in section and parts broken away.

Fig. 9 is a part sectional plan view showing the squeegee carrying arms and mechanism for lifting them.

Fig. 10 is a detail view showing the foot treadle and valves operated thereby.

Fig. 11 is a diagrammatic view of the air motors and the control system therefor.

Referring to the drawings, the machine as shown and as will now be described, is particularly adapted for decorating the bodies and shoulders of round bottles B of conventional form, but it will be understood that it may be adapted and used for decorating or printing on the surfaces of bottles and other articles of various shapes. The mechanism is mounted on a framework including a platform 21 supported on

a frame 22 having legs 23. A pair of aligned frames 24 of inverted U-shape mounted on the platform 21 and bolted thereto, extend lengthwise of the platform. The inner vertical ends of the frames 24 are spaced apart to receive the head 25 of a workholder frame, said head being slidably mounted for vertical adjustment on guide rails or ribs 26 on the inner end walls of the frames 24. A shaft 27 journalled in the head 25 carries a chuck 28 to engage the bottom end of a bottle B during the decorating operation. The neck end of the bottle is held by a neck chuck 29 carried on an arm 30 adjustably mounted on a bracket 32 attached to the head 25.

The work-holder frame is carried on a vertical screw shaft 33 supported by and adjustable up and down in the platform 21. To permit such adjustment the shaft is threaded through a bushing 34 secured to the platform and carries at its lower end a hand wheel 35. The shaft is locked in its adjusted position by a locking nut or element 36 having a hub 37 threaded on the shaft. Vertical adjustment of the work-holder permits bottles or other articles of various sizes to be adjusted to the proper height for cooperation with the decorating screens.

Referring to Fig. 7, the neck holding chuck 29 carries a pad 38 of rubber or the like for engaging the lip of the bottle. The chuck is movable to and from the work-holding position by an air operated piston motor 39. The motor piston 40 and piston rod 43 with the chuck attached thereto, are moved forward by air under pressure and retracted by a spring 42.

The cylindrical body of the bottle is decorated by means of a decorating screen 45 herein referred to as the body screen. This screen may be of conventional construction and is provided with previous portions 46 (Fig. 1) representing the designs which are applied to the bottles in a conventional manner. The shoulder portion of the bottle is decorated in like manner by a screen 47 herein termed a shoulder screen, carrying decorative designs 48. The body screen 45 is carried

in a rectangular screen frame 49 connected to a body screen carriage 51 (Figs. 1 and 6) by means of bracket arms 50, and a bar 52 attached to said arms. The bar 52 is slidably mounted in a channel formed in the carriage 51 permitting adjustment of the screen frame lengthwise of the carriage.

The shoulder screen 47 is mounted in a screen frame 53 (Figs. 1 and 3) carried at the outer ends of a pair of arms 54. Said arms are adjustably connected to and form extensions of arms 55 to

which they are clamped by bolts 56, permitting the shoulder screen to be adjusted to different positions lengthwise of the work-piece underneath. A scale 57 carried on one of the arms 55 indicates the position of adjustment. The arms 55, 54 are also adjustable vertically for adjusting the height of the shoulder screen. For this purpose each of the arms 55 is provided at its inner end with a vertical rack 58 mounted for up and down movement in a bracket 59 (see Figs. 3, 4, and 8). The brackets 59 are mounted on a shoulder screen carriage 61. Adjustment of the shoulder screen up and down is effected by means of a hand wheel 62 on an adjusting rod 63 journalled in the brackets 59 and carrying pinions 64 which engage the rack bars 58.

The body screen carriage 51, which is of rectangular construction, is slidably mounted for lengthwise reciprocation on the frames 24. Each of the frames 24 comprises spaced parallel side walls 65, on the upper surfaces of which the screen carriage 51 is slidably supported. The shoulder screen carriage 61 is also of rectangular form and supported directly on the frame 51 for relative movement lengthwise thereof.

The carriages 51 and 61 are reciprocated by an air operated piston motor 66, herein referred to as the main motor, mounted on the platform 21. The motor includes a piston 67 (Fig. 8) and piston rod 68, the latter connected to an arm 69 (Figs. 5 and 8) bolted to and extending downward from the carriage 51. Each stroke of the motor piston moves the body screen carriage lengthwise during the decorating operation and at the same time rotates the workpiece B at the same surface speed as that of the decorating screen 45. The operating connections for rotating the chuck comprise a gear wheel 70 (Figs. 3 and 8) keyed to shaft 27 and meshing with a rack bar 71 attached at its ends to vertical arms 72. The arms 72 are clamped to pins 73 fixed to and extending rearwardly from the carriage 51. The gear 70 is preferably of a pitch diameter equal to the diameter of the surface which is being decorated, the gear being removable and interchangeable with gears of other diameters for decorating work-pieces of different diameters.

Operating connections between the motor 66 and the shoulder screen include a gear 74 keyed to the shaft 27 and driving a rack bar 75 connected to the shoulder screen carriage 61. Such connection includes an arm 76 formed on the rack bar 75 and bolted to a connecting piece or bracket 77 which in turn is bolted to the carriage 61. The rack 75 is adjustable vertically for cooperation with gears 74 of different diameters corresponding to the diameter of the shoulder portion of the work-piece which is being decorated.

Squeegees 80 and 81 (see Figs. 3 and 6) cooperate with the screens 45 and 47 respectively in a conventional manner for applying the decorating material. That is to say, the squeegees are held stationary and hold the screens against the surfaces to be decorated, while the said surfaces rotate and the screens advance therewith, so that the decorating material is forced through the perforate portions of the screen comprising the designs 46, 48.

The shoulder squeegee 81 is carried by a pair of arms 82 which are keyed to a pivot shaft 83 (Figs. 6 and 9) at the inner end of said arms. The shaft 83 is journalled in a carrier 84 which supports the squeegees and which is movable up and down for periodically lifting the squeegees as hereinafter described. The shoulder squeegee 81

is connected to the arms 82 by means of a block 85 slidable lengthwise of said arms for adjusting the squeegee and is held in its adjusted position by a clamping bolt 86.

5 The body squeegee 80 is carried on an arm 87 mounted between the arms 82 for swinging movement about the axis of the pivot shaft 83. Extending forwardly from the arm 87 and attached thereto or forming an integral part thereof are parallel spaced bars 87'. The squeegee 80 is attached to a post 88 which is adjustable up and down by means of an adjusting screw 89 and is also adjustable lengthwise of the bars 87' and held in such adjusted position by a clamping nut 90.

10 The arms 82 carrying the shoulder squeegee are adjustable about the axis of the pivot 83 relative to the arm 87, 87' which carries the body squeegee, thus permitting up and down adjustment of the shoulder squeegee relative to the body squeegee. The means for effecting this adjustment will be understood by referring to Figs. 5 and 6. Such adjusting means includes an adjusting rod 91 screw threaded into the arm 87 and adjustable therein by means of a knob 92. The rod 91 is journalled in the upper end of a yoke 93 which straddles the arm 87. The lower ends of the yoke arms are provided with projections which engage beneath shoulders formed on the arms 82. The yoke 93 is formed with lugs 94 in which screw rods 95 are supported. Coil compression springs 96 are mounted on the rods 95 between the lugs 94 and nuts 97 threaded on said rods. The rods 95 at their lower ends engage the arms 82. The springs 96 apply an upward pressure to the yoke 93 and thereby yieldingly hold the arm 87 in a certain position relative to the arms 82, determined by the adjustment of the yoke 93.

15 The squeegees may be swung upward from their operative position and held up by means (Figs. 6 and 9) including a handle 100 at the outer end of a pair of rods 101 supported on the arm 87 for lengthwise movement thereof. Holding dogs 102 attached to the forward end of the rods 101 are adapted to engage notches 103 formed in a yoke 104 in which the pivot rod 83 is journalled, said yoke forming an integral part of the carrier 84. The squeegee arms are thus held in their operative position. When the handle 100 and dogs 102 are retracted against the holding pressure of coil springs 105, the squeegee arms may be swung upward by said handle to the broken line position (Fig. 6) and held in such position 20 by engagement of the dogs 102 with upper notches 106 in the yoke.

25 The carrier 84 which supports the squeegee mechanism is indirectly supported on a vertically disposed frame 107 having a fixed mounting between the adjacent ends of the frames 24. The frame 107 includes depending arms 108 at the lower end thereof for attachment to the frames 24. The connection between the carrier 84 and the frame 107 includes a piston motor 110 having a piston 111 and piston rod 109. During the decorating operation the piston is held in its lowered position by air under pressure, thereby holding the squeegees against the screens and holding the latter in contact with the work-piece. At the completion of each decorating stroke of the screens, the air pressure to the motor 110 is cut off and the piston lifted by a coil spring 113 held under compression between the carrier 84 and the frame 107.

30 The screen carriage 51 is arrested at the com-

pletion of its horizontal travel by stop devices 114 (Fig. 5). Each stop device includes a piston 115 working in a cylinder 116. The piston carries a pad 117 of rubber or the like to engage the screen carriage. When the carriage strikes a piston as it approaches the end of its travel, the piston is moved inwardly, compressing the air within the cylinder and arresting the carriage with a dash pot action. The air is permitted to escape from the cylinder through a restricted passageway controlled by an adjustable throttle valve 118. The stop devices 114 are mounted for sliding movement along the walls 65 of the frames 24, for adjustably varying the positions at which the screen carriages are stopped. The adjustment is effected by means of an adjusting rod 120, journalled in the outer ends of the frames 24 and carrying a hand wheel 121. The adjusting devices are formed with internally screw threaded bearings 122 for right and left-hand screw threads formed on the rod 120.

The pneumatic system for operating and controlling the decorating mechanism will now be described. Referring to Fig. 11, air under pressure is supplied through a pressure regulator 125 to a pressure tank 126. Air under pressure is supplied from the tank through a pressure pipe 127 to a rotary valve 128. The valve is rotated step by step by a piston motor 131 for connecting opposite ends of the main motor 66 alternately with the pressure supply through pipes 129 and 130. The motor 131 also functions as a valve to control the air supply from a pressure pipe 132 to the motor 110 for lifting the squeegees, air pressure being transmitted from the valve 131 through a pipe 133 to motor 110. The valve 131 also controls the air pressure supplied through a pipe 134 to the motor 39 for operating the chuck. The piston motor 131 is operated by air supplied through a pressure line comprising pipes 135 and 137 leading respectively to and from a valve box 136.

Fig. 10 illustrates the manual control device including a foot pedal 138 pivotally mounted on the valve box 136. A valve 140 in the valve box is normally held closed by its spring, thereby closing the pressure line including the pipe 135 which opens into the valve box through a port 135a and the pipe 137 which opens into the valve box through a port 137a. A valve 141 controlling an exhaust port 142 is held open by a tappet 143 on the foot pedal, the latter being held in the position shown by a coil spring 144. When the foot pedal is depressed, the tappet 143 is lifted, permitting the valve 141 to close and the valve 140 then is opened by a tappet 145. Air is thus supplied through pipe 137 to the valve motor 131 (Figs. 8 and 11). This imparts an operating stroke to the motor piston 146. As the piston advances it first opens a port to the pipe line 134 leading to the chuck operating motor 39 so that the latter operates to grip the work-piece. Continued forward movement of the piston 146 opens communication to the pipe 133 leading to the motor 110 so that the latter operates to lower the squeegees into operative position.

The forward stroke of the piston 146 also operates through a connection 147 to impart a step rotation to the rotary valve 128 for effecting an operation of the main motor 66. The valve 128 which may be of conventional construction is rotated through an angle of 60 degrees during each forward stroke of the piston 146, thereby connecting each end of the motor 66 alternately

with air pressure and exhaust. With the parts in the position shown in Fig. 11, the pressure pipe 127 is connected through the valve 128 to the pipe 130 for holding the motor piston at the left-hand end of the cylinder. When the foot pedal is actuated and the valve 128 rotated, as above described, the pipe 130 is opened to exhaust and the pipe 129 connected to the pressure pipe 127, thereby operating the motor 66.

- 10 The operation may be summarized as follows: The operator places a bottle B in position on the chuck 28 with the neck of the bottle resting on a guide plate 148 (Fig. 6) which holds it in line with the chuck 29. The rotative position of the bottle is indicated by pointers 149 (Figs. 2 and 3) adjustably mounted on stationary rods 150. The bottle may be rotated by hand to bring a side seam or other indicating mark in line with a pointer 149. The foot pedal 138 is now depressed thereby supplying air to the motor 131 so that it operates, first to actuate the chuck motor 39 and cause the chuck 29 to clamp the bottle, then to actuate the motor 110 and move the squeegees downward to hold the screens against the surfaces to be decorated, and then to supply air pressure for operating the main motor 66. The latter advances the body screen carriage with the body of the work-piece in rolling contact with the screen, and through the rack and pinion 71, 70 (Fig. 8) rotates the work-piece at the same peripheral speed. At the same time the shoulder screen 47 is advanced through the rack and gear connections 75, 74, at a slower speed corresponding to the diameter of the shoulder portion which is being decorated. The body screen carriage is arrested at the completion of its stroke by the buffer stop 114. The operator then releases the foot pedal, permitting the motor piston 146 (Figs. 8 and 11) to be returned as by means of a coil spring 151, thereby causing the chuck 29 to be retracted and the squeegees lifted. This permits the bottle to be removed and another one placed in position to be decorated during the movement of the carriages in the opposite direction.

Modifications may be resorted to within the spirit and scope of my invention.

I claim:

- 50 1. Decorating apparatus comprising a motor, a screen frame, a screen carried by said frame, operating connections between the motor and said frame for reciprocating the latter, a work-holder, means for securing a work-piece to the work-holder, driving connections between the work-holder and the motor for rotating the work-holder with the work-piece in rolling contact with the screen, a second screen frame and screen, and driving connections between the second screen frame and the work-holder by which said second screen is driven by the work-holder at a different speed from the first screen.
- 55 2. Decorating apparatus comprising a screen carriage, means for reciprocating the carriage, a screen connected to the carriage, a work-holder including a shaft, a driving connection between the shaft and said carriage for rotating the work-holder when the screen is reciprocated, a second screen carriage, a screen carried thereby, and driving connections between said shaft and said second carriage for reciprocating the latter at a speed different from that of the first mentioned carriage.
- 60 3. Decorating apparatus comprising in combination screen carriage, screens carried thereby, a shaft, a work-holding chuck carried by said

shaft, pinions of different diameters keyed to said shaft, racks connected respectively to said carriages and running in mesh respectively with said pinions, and means for driving one of said carriages and causing the latter to rotate said shaft and thereby drive the other carriage.

4. Apparatus for decorating round bottles comprising a body screen frame and screen, a shoulder screen frame and screen, body and shoulder screen carriages to which said screen frames are respectively connected, a motor having a driving connection with the body screen carriage, a chuck for holding a bottle, a shaft carrying said chuck, gears keyed to said shaft, and racks meshing respectively with said gears and mounted respectively on said carriages, said gears being of different diameters corresponding to the diameters of the body and shoulder portions of the bottle to which the screen decorations are applied.

5. Apparatus for decorating round bottles comprising a body screen frame and screen, a shoulder screen frame and screen, body and shoulder screen carriages to which said screen frames are respectively connected, a motor having a driving connection with the body screen carriage, a chuck for holding a bottle, a shaft carrying said chuck, gears keyed to said shaft, and racks meshing respectively with said gears and mounted respectively on said carriages, said gears being of different diameters corresponding to the diameters of the body and shoulder portions of the bottle to which the screen decorations are applied, said gears being interchangeable with other gears of different diameters, said racks being adjustable to actuate gears of different diameters and said shaft being adjustable toward and from the screens for operatively positioning bottles of different diameters relative to the screen.

6. Apparatus for simultaneously applying decorations to different surface portions of a round article, said surface portions being of different diameters, said apparatus comprising means for rotating said article about a horizontal axis, screens positioned for respectively engaging said surfaces, squeegees cooperating respectively with said screens, arms to which said squeegees are respectively attached, said arms being relatively rotatable about a common horizontal axis, means for holding said arms at a predetermined relative position of rotation about said axis, means for rotatively adjusting one said squeegee and its carrying arm about said axis relative to the other squeegee, and means for lifting and lowering the squeegees and their carrying arms bodily as a unit from and to their operating positions.

7. Apparatus for simultaneously applying decorations to different surface portions of a round article, said surface portions being of different diameters, said apparatus comprising screens for respectively engaging said surfaces, squeegees

cooperating respectively with said screens, arms to which said squeegees are respectively attached, said arms being relatively rotatable about a common axis, means for holding said arms at a predetermined relative position of rotation about said axis, manual means for swinging said squeegees and arms as a unit about said axis for moving the squeegees to operative and inoperative positions, means for holding the arms and squeegees in each of said positions, and automatic means for lifting and lowering the squeegees and their carrying arms bodily as a unit from and to their operating positions.

8. Decorating apparatus comprising in combination a body squeegee, a shoulder squeegee, an arm on which the body squeegee is carried, an arm on which the shoulder squeegee is carried, said arms being relatively movable about a common axis, means for yieldingly holding said arms in a predetermined relative position, means for adjusting one said arm about said axis relative to the other arm, means for adjusting each of said squeegees lengthwise of its supporting arm, and means for adjusting one of said squeegees in a direction transversely of its supporting arm.

9. Apparatus for decorating bottles comprising a body screen frame and screen, a shoulder screen frame and screen, a body squeegee cooperating with the body screen, a shoulder squeegee 30 cooperating with the shoulder screen, a pair of spaced arms carrying the shoulder squeegee, a pivot shaft on which said arms are mounted, an arm carrying the body squeegee and mounted to swing about the axis of said pivot shaft, means for holding the arms which carry the shoulder squeegee in a predetermined position relative to the arm which carries said body squeegee, and means for adjusting the shoulder squeegee arms relative to the body squeegee arm.

10. Apparatus for decorating bottles comprising a body screen frame and screen, a shoulder screen frame and screen, a body squeegee cooperating with the body screen, a shoulder squeegee cooperating with the shoulder screen, a pair of spaced arms carrying the shoulder squeegee, a pivot shaft on which said arms are mounted, an arm carrying the body squeegee and mounted to swing about the axis of said pivot shaft, means for holding the arms which carry the shoulder squeegee in a predetermined position relative to the arm which carries said body squeegee, and means for adjusting the shoulder squeegee arms relative to the body squeegee arm, said holding and adjusting means including a yoke, a screw shaft journaled in the yoke and having a threaded connection with the body squeegee arm for adjusting the yoke, and spring means for yieldingly holding the shoulder squeegee arms in a predetermined position relative to said yoke.
